UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

METHOD OF TABLE-TOP CONSTRUCTION.

Application filed March 18, 1925. Serial No. 16,304.

This invention relates to a table top construction, and has for its object the construction of a table which has incorporated there-in a silencing pad which is so secured to the table as to be practically an integral part thereof. The ordinary metal, stone or tile tables are very hard and noisy. Great care must be exercised in setting down dishes, or the like, on such a table, as fragile articles 10 may be easily broken if they are slammed down with any amount of force. The object of incorporating a silencing pad on the table is to lessen the liability of breaking dishes and the like when being set on the table, and 15 also this eliminates the noise resulting from setting them thereon.

In the drawings:

Fig. 1 is a perspective view of a table top.

Fig. 2 is a section taken on the line 2—2 20 of Fig. 1.

Fig. 3 is a vertical section through a mould showing the process of casting the moulding to the table slab.

Fig. 4 is a sectional view of the completed 25 slab when removed from the mould.

Fig. 5 is a detailed section of a modified form of construction in which the linoleum is dove-tailed in the stone moulding.

The table consists of a reinforcing slab *a*, 30 preferably made of wood. Secured to this slab by any suitable adhesive material is a silencing pad *b* which is smaller in area than the slab *a*, the edges of the pad being set in from the edges of the wood slab. This slab 35 and pad are now dropped into the mould *c* and suitably spaced from the side walls of the mould by the brackets *d*, as shown in Fig. 3. An artificial stone mixture is now poured into the space between the slab and mould, and I preferably use for this artificial stone an oxy-chloride cement. The nails *e*, or other suitable fastening devices, may be driven into the wooden slab, and when the 40 artificial stone is allowed to rest for a definite length of time the moisture therein evaporates and the stone sets, the heads of the 45 nails being embedded in the stone and keying the stone moulding to the slab.

It will be noticed from the drawings how 50 this cast stone moulding *f* is cast-united to the peripheral edge of the wooden slab and laps over the edge and contacts with the edge of the linoleum or silencing pad. This construction obviously provides a smooth 55 surface for the top of the table as the stone

contacts closely and is flush with the edge of the silencing pad.

In Fig. 5 I show a slightly modified form of construction in which the silencing pad is provided with beveled edges to allow the stone moulding to lap over a greater distance at the surface of the table than at the base of the silencing pad. This forms a sort of dove-tail and such a silencing pad cannot be removed except by buckling the 60 pad as the stone moulding securely locks the same in place. With the construction as shown in the other figures, it would be possible to pry out the linoleum by breaking the union between the slab and pad, although 65 this would probably not be done very often, as the linoleum pad will wear for a considerable length of time.

What I claim is:

1. A method of table top construction, 75 which comprises the inserting of a slab serving as a base and provided with a silencing pad into a mould in spaced relation therewith, and the casting of a continuous artificial stone moulding about the peripheral edge of said slab and silencing pad.

2. A method of table top construction, 80 which comprises the securing of a silencing pad serving as a base to a reinforcing slab, the inserting of said slab and a pad in a mould in spaced relation therewith, and the casting of a continuous artificial stone moulding about the peripheral edge of said slab and silencing pad.

3. A method of table top construction, 85 which comprises the inserting in a mould of a slab provided with a silencing pad having the edges thereof set in from the edges of the slab, and the casting of a continuous artificial stone moulding about the peripheral edge of said slab and slightly lapping the stone over the edge of said slab to closely contact the stone moulding with the inset edge of the silencing pad.

4. A method of table top construction, 90 which comprises the inserting of a slab provided with a silencing pad and fastening devices along the edge thereof into a mould in spaced relation therewith, and the cast-uniting of a continuous artificial stone 95 moulding to said slab about the peripheral edge thereof.

5. A method of table top construction, 100 which comprises the inserting of a reinforcing slab serving as a base and provided with 105

a silencing pad of linoleum into a mould in spaced relation therewith, and the casting of a continuous artificial stone moulding about the peripheral edge of said slab and linoleum silencing pad.

6. A method of table top construction, which comprises the cementing to a reinforcing wooden slab of a pad of linoleum having the edges thereof set in from the edges of 10 the wooden slab, the inserting of said slab and pad united therewith into a mould in spaced relation therewith, and the casting of a continuous artificial stone moulding about the peripheral edge of said slab, said moulding overlapping the edge of the slab to closely contact in liquid tight relation with the inset edges of said linoleum silencing pad.

7. A method of table top construction 20 which comprises the inserting of a slab in a mould, and the casting of a continuous moulding about the peripheral edge of said

slab serving as a finishing edge for a table top finishing pad secured to the face of said slab.

8. A method of table top construction which comprises the inserting of a slab in a mould, and the casting of a continuous moulding of artificial stone about the peripheral edge of said slab serving as a 30 finishing edge for a table top finishing pad secured to the face of said slab.

9. A method of table top construction, which comprises the securing of a silencing pad to a slab, the inserting of said slab and pad in a mould in spaced relation therewith, and the securing of a continuous stone moulding about the peripheral edge of said slab substantially flush with the face of said silencing pad.

In testimony whereof I have affixed my signature,

LLOYD G. COPEMAN.
